UNITED STATES PATENT OFFICE.

WILLIAM E. GOODENOUGH, OF NEWARK, NEW JERSEY.

CRIBBAGE-BOARD.

SPECIFICATION forming part of Letters Patent No. 245,157, dated August 2, 1881.

Application filed May 14, 1881. (Model.)

To all whom it may concern:

Be it known that I, WILLIAM E. GOODENOUGH, a citizen of the United States of America, residing at Newark, in the county of 5 Essex and State of New Jersey, have invented certain new and useful Improvements in Cribbage-Boards; and I do hereby declare the following to be a full, clear, and exact description of the invention, such as will enable others 10 skilled in the art to which it appertains to make and use the same, reference being had to the accompanying drawings, and to letters or figures of reference marked thereon, which form a part of this specification.

15 This invention relates to the manufacture of cribbage-boards, and to improved means for marking the games of cribbage and whist; and it has for its object to provide a cheap and substantial marking-board, with a series of 20 counters or pins, so secured that they cannot be lost, and from which the count of the game can be accurately and readily ascertained.

25 My invention therefore consists in a cribbage-board composed of one or more sections 25 of wood or other suitable material, provided on each side with grooves or slots graduated in groups for the purpose of receiving markers or counting-pins.

30 My invention also consists in a cribbage-board formed of two or more sections of wood or other suitable material, provided on each side with vertical grooves or slots graduated in groups, and also having in each side a horizontal groove cut for the purpose of receiving 35 and retaining marking pins or counters.

My invention further consists in a cribbage 35 marker or counting-pin of the construction as hereinafter described.

40 My invention further consists in a cribbage-board formed of sections having on each side vertical grooves or slots, and also on each side a horizontal groove or slot and means for bushing the horizontal slots after the insertion of the markers or counting-pins, as hereinafter 45 described.

45 My invention further consists of a cribbage-board formed of two or more sections provided with vertical slots and a horizontal slot on each side, in combination with a central section 50 having vertical slots or grooves, and a

horizontal groove for the purpose of receiving and retaining movable markers or counting-pins to designate the number of games played.

55 My invention further consists in a cribbage-board formed of two or more sections having vertical slots or grooves arranged in groups and a horizontal slot or groove on each side, in combination with markers or counting-pins inserted in said slots.

60 My invention further consists in a cribbage-board formed of two or more sections and a central section-piece having vertical slots or grooves and a horizontal slot or groove in each side, in combination with a series of markers or counting-pins, for the purpose of designat- 65 ing the number of games played.

65 My invention further consists in the novel construction and combination of parts, as will be hereinafter more specifically described and claimed.

70 Reference being had to the accompanying drawings, Figure 1 is a perspective view of my improved cribbage-board. Fig. 2 is a side view, showing the border or casing removed. Fig. 3 is a perspective view of a part of a section of one of the strips, showing the construction of the same and pins inserted. Fig. 4 is a side view of a portion of one of the sections or blocks, showing the vertical and horizontal slots or grooves and one of the pins inserted. 75 Fig. 5 is a view of one of the markers or counting-pins; and Fig. 6 is a view of one of the markers or counting-pins, showing a modification with the axis on opposite sides.

80 In the manufacture of my cribbage-board I take strips of wood, A, of a given length, width, and thickness, (see Fig. 3,) and form in the sides thereof, by sawing or other suitable means, a series of vertical slots or grooves, a, arranged in groups for the convenience of 85 numbering the points played in the game, and at right angles to these grooves, below the center of the strip, is formed a horizontal slot or groove, b, of nearly the same depth as that of the vertical slots.

90 A section of the board is shown at B, where- 95 in the pins or counters are represented in position in the slots, and the bushing and retaining-strip fixed in the horizontal slot. This bushing consists of any suitable material, pref- 100

erably cotton or linen cording, forced and held in the horizontal slot over the base or heels of the pins by a closely-fitting wooden strip or other suitable material.

5 The letter F (see Fig. 5) represents the marker or counting-pin, formed with a head, and a heel bent or curved at a suitable angle to fit the horizontal groove, the bent portion forming an axis for the pin or counter. These vertical slots should be cut directly across the side of the strip or section and deep enough to allow the lateral movement of the pins or counters, sufficient to suit the purposes of readily discerning the count of the game from 10 the number of points not made.

15 The blocks or solid portions *c*, above the horizontal slot, and between the vertical slots, are beveled on one of the lower corners, in order to fit the angle of the pin and permit the 20 lateral movement without undue pressure. The blocks below the horizontal slot form the bases for the heels of the pins to rest upon, and those above the slot prevent the pins from being dropped or pulled out when in position. These sectional groups are multiplied 25 until the numbers reach the requirements of the game.

30 The letter C represents the central section of the board, provided with pins to serve as counters of the number of games played. These pins are of the same shape, fit in like slots, and are secured in the same manner as those of the outside strips. At each end of this central piece are cut the slots *d* and *d'*, as shown 35 in the drawings, and in each a single pin is put, and secured by the same means as the others are.

35 After the different sections and parts of the board are prepared, substantially as described, 40 the pins or counters are inserted in the slots or grooves until the heel or axis reaches the horizontal slot, when they are turned into it, and the bushing and holding-strip put in the groove. The pins in the central section are 45 inserted and secured in the same manner as those in the side strips. The separating-strips may now be prepared, and the parts adjusted and secured together in the order shown in the drawings in Fig. 1. Glue may be used 50 to join the parts together, and additional firmness and durability guaranteed by means of screwing them together, after which a bottom board may be screwed or pinned on the bottom, and the border or casing put around the 55 sides.

55 The casing, it will be seen, serves to confine the outside rows of pins to the limits of the vertical slots. The pins or markers in the central strip are intended to mark the number of 60 games played, but they may also be used as markers in the game of whist.

65 In counting a game of cribbage the pins or markers may be arranged in each section with their heads inclined toward each other, or in opposite directions, or in the same direction. The count of the game, of course, in any case

will break the line in an opposite direction from the arrangement fixed upon by the players.

70 It will be readily seen that the counting of a game is materially expedited by this arrangement of the markers, and that its condition can be at once and at any time quickly and accurately determined.

75 It is obvious that the horizontal slot or groove may be placed at the bottom of the section instead of in the sides, and also that the board may be manufactured of iron or other metal, and also that it may be covered with velvet or similar materials.

80 I reserve the right to slightly change the construction of the parts as well as the material, without departing from the spirit of the invention herein described.

85 What I claim as my invention, and desire to secure by Letters Patent, is—

1. A section or block for a cribbage-board with a series of vertical slots or grooves formed in the sides thereof, substantially and for the purpose set forth.

90 2. A section or block for a cribbage-board with a series of vertical slots or grooves and a longitudinal slot or groove formed in the sides thereof, substantially and for the purposes set forth.

95 3. In a cribbage or similar game board, a section or block formed with a series of vertical slots or grooves and a horizontal groove, and the marking pins or counters fastened in said grooves or slots by means of bushing arranged in the horizontal groove, substantially 100 as described.

105 4. A marking or counting pin for a cribbage-board or similar game-board, having its lower end bent or curved, substantially as shown, and for the purpose stated.

110 5. In a cribbage or similar game board, the combination of the sections or blocks formed with the side vertical, and longitudinal grooves or slots, and the series of marking or counting pins arranged in said slots or grooves, secured from displacement, but capable of a shifting motion, substantially as described.

115 6. In a cribbage or similar game board, the combination of the sections or blocks formed with the side vertical, and longitudinal grooves or slots, the series of marking or counting pins arranged in said slots or grooves, and the bushing composed of a soft packing, and a wooden strip or other suitable material, substantially 120 as described.

125 7. A cribbage or similar game board formed of two or more sections or blocks provided with shifting marking or counting pins working on axes, substantially as described.

130 8. A cribbage-board formed of two or more sections or blocks provided with shifting marking or counting pins working on axes, with a central section or block provided with shifting-pins working on axes, to designate the number of games played, substantially as described.

9. A cribbage - board composed, essentially, of two side sections or blocks provided with a double row of axial - working marking-pins or counters arranged in groups, and a central section or block provided with end axial-working pins to mark the termination of the game, and axial-working pins to designate the number of games played, substantially as described.

In testimony whereof I affix my signature in presence of two witnesses.

WILLIAM E. GOODENOUGH.
